UNITED STATES PATENT OFFICE.

A. PUTNAM, OF OWEGO, NEW YORK.

IMPROVEMENT IN GRAIN-DRILLS.

Specification forming part of Letters Patent No. 55,707, dated June 19, 1866.

To all whom it may concern:

Be it known that I, ARCHIBALD PUTNAM, of Owego, in the county of Tioga and State of New York, have invented a new and useful Improvement on a Grain-Drill and Broadcast Sower Combined; and I do hereby declare that the following is a full, clear, and exact description of the construction and operation of the same, reference being had to the annexed drawings, making a part of this specification, in which—

Figure 1 is a perspective view; Fig. 2, a longitudinal elevation; Fig. 3, a latitudinal elevation; Fig. 4, a transverse section; Fig. 5, a transverse section; Fig. 6, a transverse section.

The nature of my invention consists, first, in an improvement upon the combination of two separate machines into one—viz., the broadcast sower and the grain-drill.

To enable others skilled in the art to make and use my invention I will proceed to describe its construction and operation.

The feed-box is placed upon the center of the machine in the usual way, as seen in Figs. 1 and 2, and its form and the general construction of the machine throughout are similar to those already in use, except the arrangement of the hollow teeth, which will be hereinafter described.

Figs. 1 and 4 show the machine arranged for broadcast, the grain being fed or distributed in the usual way, and dropped through holes in front of the teeth.

The changing of the machine from a broadcast sower to a grain-drill, and from a grain-drill to a broadcast sower, consists in adjusting the openings through the tooth-bars to the feed-box instead of adjusting the feed-box to the openings D E, which is done by raising the front end of the tooth-bars K out of the notch C and sliding them back to notch B, which brings the openings D, for sowing broadcast, directly under the feed-box F, as seen in Fig. 4, at the same time moving the block L,

which supports the lifting-roller M, to the back end of slot I, as seen in Fig. 1, and to change the machine from broadcast to drill is vice versa.

It will be seen that the feed-box remains stationary in the center of the machine, thereby leaving the machine always balanced, instead of moving it forward to make a broadcast, which throws the load upon the horses' necks, or moving it to the rear of the axle to make a drill, which has a tendency to raise the tongue, thereby throwing the machine always out of balance, which is the difficulty of all combined machines heretofore in use.

The second feature is in the arrangement of the teeth. It may be seen by the annexed drawings that the tops of the teeth or openings which communicate with the feeding apparatus are all in a straight line, as usual, as shown at Fig. 3, but that the teeth are made from two different-shaped patterns—that is to say, every other tooth is formed with the foot or point projecting ahead of that on either side, as shown at G H, the arrangement of which brings the points of the teeth double the distance from each other that they are at the top, thereby obviating the common difficulty which has hitherto existed by clogging with stones, sods, stubble, &c.

What I claim, and desire to secure by Letters Patent, is—

1. The changing of the machine from a grain-drill to a broadcast sower, and from a broadcast sower to a grain-drill, by moving or adjusting the tooth-bars K to the feed-box F, as above described, or its equivalent.

2. By forming the teeth G and H from two different-shaped patterns, which is to incline one forward and the other backward, alternately, in the manner already set forth and described.

ARCHIBALD PUTNAM.
